FLUID TURBINE

Filed Nov. 7, 1924

FIG. 1.

FIG. 2.

FIG. 3.

FIG. 4.

FIG. 5.

INVENTOR

John A. Choquette
BY *Donald S. Penny*
HIS ATTORNEY

UNITED STATES PATENT OFFICE.

JOHN ALBERT CHOQUETTE, OF OTTAWA, ONTARIO, CANADA.

FLUID TURBINE.

Application filed November 7, 1924. Serial No. 748,404.

This invention relates to improvements in a fluid turbine and has for a particular object to provide a device of that class having a rotor acted on by a tangentially directed force feed the velocity of which is increased by the diminution of the raceway dimensions.

A further object is to provide such a turbine comprising a pair of segments, each having a feed and a discharge opening acting individually on the rotor and a diagonally opposite pair of velocity increasing elements.

To the accomplishment of these and related objects, my invention resides in the construction, combination and arrangement of parts as shall be hereinafter more fully described, illustrated in the accompanying drawings and pointed out in the claims hereunto appended.

In the drawings forming a part of this disclosure, wherein like characters of reference indicate like parts throughout the several views,

Fig. 1 is a longitudinal vertical section of an embodiment of this invention;

Fig. 2 is a side elevation thereof;

Fig. 3 is a transverse vertical section taken on the line 3—3 of Fig. 1;

Fig. 4 is an end elevation and

Fig. 5 is a perspective of the means employed for mounting and moving the velocity increasing elements.

This improved turbine is housed within a cylindrical casing 6 having ends 7 removably applied thereto by the bolts 8. A rotor 9 mounted on the shaft 10 that is journalled in the ends 7 has longitudinal ribs or vanes 11 extending angularly therefrom.

A diagonal pair of fluid inlet ports 12 and 13 respectively are threaded to receive the supply pipes (not shown). The outlet discharge ports 14 and 15 are adjacent though spaced from said inlets and intermediate the adjacent pairs of said ports are inwardly directed extensions 16 and 17 that have frictioned clearance with the vanes 11. As will be noted on reference to the drawings, these extensions with a straight face adjacent the discharge port provide interruption for the spent fluid directing it through the said outlet while the incline of the remote side forming a continuance of the inlet or feed

port projects the fluid on the tangent of the rotor 9. It will thus be apparent that two raceways 18 and 19 are provided in which two independent, individual and distinct forces are applied to the rotor 9 without in any way interfering with or hindering the operation and effectiveness of the other.

The rate of revolution of the wheel 9 which is dependent on the velocity and pressure of the motive imparting fluid such as water or a liquid fed through the inlet ports 12 and 13 is increased by the provision of raceway dimension diminishers 20 one of which is mounted in each raceway and preferably diagonally opposite each other.

These velocity increasing elements 20 are inward extensions from the casing 6 disposed transversely of the lines of pressure in the raceways and may be formed integral with said casing. The present embodiment however illustrates these current deflectors 20 as being carried by discs 21 and 22 that are interposed between the ends of the casing and the rotor 9. This is to provide for adjustment of their position and the hub of disc 21 projecting through the end of the casing 7 as at 23 provides a bearing for the shaft 10 thereat and terminates in a gear 24 with which a manually operable worm 25 co-operates.

The deflectors above described may be provided with an inclined face on the pressure side and if adjustable will contact closely with the inner wall of the casing; thus by reducing the passage an increased velocity is provided without creating any material back pressure. So it will be seen that by the actuating of the manually operated worm 25, these diametrically opposite deflectors 20 may be adjusted circumferentially to increase or diminish the "head" of the driving propellant or to act as closures for either the inlet or outlet ports.

From the foregoing description taken in connection with the accompanying drawings, it will be manifest that a fluid turbine is provided which will fulfill all the necessary requirements of such a device but as many changes could be made in the above description and many apparently widely different embodiments of my invention constructed within the scope of the appended claims without departing from the spirit or scope

thereof, it is intended that all matters contained in the said accompanying specification and drawings shall be interpreted as illustrative and not in a limited sense.

5 What I claim as new and desire to secure by Letters Patent is:

1. In a turbine of the character described, the combination of a cylindrical casing having a pair of diametrically opposed fluid discharge ports, a pair of diametrically opposed fluid inlet ports provided closely adjacent said discharge ports, inwardly extending projections between each adjacent pair of inlet and discharge ports; and a 10 rotor housed within said casing, said inwardly extending projections being in substantially fluid tight contact with or proximity to said rotor, and circumferentially adjustable means for restricting the space 15 between the vanes of the rotor and the casing at a point between said projections.

2. In a turbine of the character described, the combination of a cylindrical casing having a pair of diametrically opposed fluid discharge ports, a pair of diametrically opposed fluid inlet ports provided closely adjacent said fluid discharge ports, and inwardly extending projections between each adjacent pair of inlet and discharge ports, to direct 20 fluid tangentially onto the vanes of the rotor and from the vanes into the discharge ports; a rotor housed within said casing, said inwardly extending projections being in substantially fluid tight contact with or proximity to said rotor, diametrically opposed wedge-shaped members in fluid tight contact with the casing and parallel to the axis of the rotor, disks for rigidly connecting said members, interposed between the ends of 25 the rotor of the casing, and means for rotating said disks from the exterior of the casing.

3. In a turbine of the character described,

the combination of a cylindrical casing having a pair of diametrically opposed fluid discharge ports, a pair of diametrically opposed fluid inlet ports provided closely adjacent said discharge ports and inwardly extending projections between each adjacent pair of inlet and discharge ports, and shaped on one side to direct fluid from the inlet ports tangentially onto the vanes of the rotor and on the other side to direct the fluid from the vanes into the discharge ports; a 50 rotor housed within said casing, said inwardly extending projections being in substantially fluid tight contact with or proximity to said rotor; and circumferentially adjustable means for restricting the space 55 between the vanes of the rotor and the casing at a point between said projections.

4. In a turbine of the character described, the combination of a cylindrical casing having a pair of diametrically opposed fluid discharge ports, a pair of diametrically opposed fluid inlet ports provided closely adjacent said fluid discharge ports, and inwardly extending projections between each adjacent pair of inlet and discharge ports and shaped 60 on one side to direct fluid from the inlet ports tangentially onto the vanes of the rotor and on other side to direct the fluid from the vanes into the discharge ports; a rotor housed within said casing, said inwardly 65 extending projections being in substantially fluid tight contact with or proximity to said rotor; diametrically opposed wedge shaped members in fluid tight contact with the casing and parallel to the axis of the rotor; 70 disks, for rigidly connecting said members, interposed between the ends of the rotor and the casing and means for rotating said disks 75 from the exterior of the casing.

In testimony whereof I hereunto affix my 80 signature.

JOHN ALBERT CHOQUETTE.
